AUTOMATIC STOPPING AND STARTING DEVICE FOR GASOLINE ENGINES

Application filed June 3, 1926. Serial No. 113,519.

Our invention relates to automatic stopping and starting devices for gasoline engines, and more particularly to such devices for use in systems for automatically refrigerating transportation vehicles. While our system has been shown for illustrative purposes in connection with a refrigerator or freight car, it is to be understood that it may be used in connection with other transportation vehicles having a closed storage compartment such as closed trucks. An object of the invention is to provide a combination consisting of an ammonia compressor from which ammonia is circulated through pipes placed in the vehicle, a motor preferably a gasoline engine for driving the ammonia compressor, and means for automatically starting and stopping the motor so as to keep the temperature in the vehicle between desirable maximum and minimum limits which limits may be determined by the character of the food products or other articles which are being transported in the vehicle. Another object of the invention is to provide a starting and stopping mechanism of such construction and arrangement that it may be readily installed together with an air compressor and a motor in a vehicle so as to occupy a minimum amount of space, thus enabling the greater portion of the vehicle to be utilized for carrying the food products or other materials.

The full objects and advantages of our invention will appear in connection with the detailed description thereof, and the novel features of our inventive idea will be particularly pointed out in the claims.

In the accompanying drawings which illustrate one of the forms in which our invention may be embodied,—

Fig. 1 is a view of a car in longitudinal vertical section showing our invention applied thereto. Fig. 2 is a fragmentary view in vertical section on the line 2—2 of Fig. 1 but on an enlarged scale. Fig. 3 is a fragmentary view in horizontal section on the line 3—3 of Fig. 1. Fig. 4 is a fragmentary view illustrating the arrangement of pipes for cooling the compressed ammonia. Fig. 5 is a view showing a wiring diagram with the

parts in starting position. Fig. 6 is a view showing a wiring diagram with the parts in stopping position.

Referring to the construction shown in the drawings, the numeral 10 designates in general a transportation vehicle which in the embodiment shown may be considered as representing a freight car. In one end of the car, a bunker or auxiliary compartment 12 is produced by a vertical partition 14 of insulating material which extends from one side to the other of the car and from top to bottom thereof so as to completely isolate this compartment from the main compartment of the car. Within the compartment 12 there is an ammonia compressor 16 which is operated by a gasoline engine 18, the starting and stopping of which is automatically controlled by mechanism which will be described later and which is so designed that all of it with the exception of a thermostat may be placed in the compartment 12. A pipe 20 leads from the compressor 16 to a cooling device in which this pipe is carried back and forth in sinuous form, the straight portions of which are placed in concentrically surrounding pipe members 22, the ends of which are connected with headers 24 in well known manner. The headers and the pipes 22 outside of the sinuous portion of the pipe 20 are supplied with cooling water from a tank 26 located underneath the floor of the car. A pump 28 driven by the engine 18 takes water from the tank and forces it through a pipe 30 into the headers and the cooling pipes 22 from which it returns to the tank through a pipe 32. The pipe 20 after it leaves the cooling device continues to a reducing valve 34 from which it continues to a place near the roof of the car where it is bent back and forth in sinuous form between the ends of the main compartment of the car, the members of the pipe being designated by the numeral 36. These pipe members are held in place by transverse strips 38 which are bent into shape to encircle the pipe members and are secured to the underside of the room. One of the members 36 preferably at the end of the car opposite the auxiliary compartment 12 is provided with a plug 39.

by means of which ammonia may be introduced into the circulating system. From the return end of the members 36, a pipe 40 leads back to the compressor 16. A gasoline tank 42 is connected with the engine 18 by a pipe 44 for supplying fuel thereto. A thermostat 46 is placed in the main compartment of the car. As will be understood from Figs. 5 and 6, the thermostat embodies a movable contact member 48 adapted to swing between the fixed contacts 50 and 52. Assuming that the compartment containing the thermostat reaches the maximum temperature which is permissible, the member 48 swings into engagement with the contact 50, thus completing a circuit from a battery 54 through a wire 56, contact 50, wire 58 and coil 60 surrounding the upper portion of a solenoid core 62. The energizing of the coil 60 pulls up the core 62 and the contact member 64 carried thereby causing the latter to engage two contacts 66 and 68 so that current will flow through a wire 70 to the engine ignition 72 and will also flow through a wire 74 through the coil of an electromagnet 76 and through a wire 78 to one part of a ring 80 which has another part insulated therefrom and connected by a wire 82 with a ground 84. Connection is made from the first part of the ring 80 to the second part thereof through three arms 86 pivoted to a member 88 rotated by the engine so that these arms which at slow speed are held by springs 90 in engagement with the ring 80 may at greater speed of the engine fly out from engagement with the ring. The energizing of the electromagnet 76 draws up its armature 92 into engagement with two contacts 94 and 96, so that a circuit is completed from the battery 54 to a single unit starter-generator 102 which at this time operates as a starting motor through a gear 104 on its shaft to start or crank the engine 18 previously referred to. When the engine has control of its load and is properly speeded up, the three arms 86 fly out under operation of centrifugal force and break contact with the ring 80 and this action breaks the circuit which energizes the coil of the electromagnet 76, thus allowing the armature 92 to drop from the contacts 94 and 96 and stopping flow of current from the battery to the device 102. This device then becomes a generator and causes current to flow through a wire 100 which is divided adjacent a cut-out device 98 so that the current first flows through a coil around the lower portion of the core of the cut-out to a ground which causes the armature 106 to be drawn down and complete a circuit through a coil around the upper portion of the core and through a contact device 108 to the battery 54. When the temperature in the compartment falls to the permissible minimum, the operation indicated in Fig. 6 occurs. The movable member 48 of the thermostat swings

into engagement with the contact 52 and current then flows through a wire 110 and the coil 112 which surrounds the lower part of the solenoid core 62 and this draws the contact member 64 out of engagement with the contacts 66 and 68 which up to this time have acted as spring holders for the member 64. This operation restores the parts to their former position, thereby shutting off the engine ignition and stopping the engine and cooling system.

The operation and advantages of our invention have to a large extent already been set forth. As will be understood from Fig. 1, the greater portion of the apparatus is placed in compact arrangement within a special auxiliary compartment which may be readily fireproofed so as to reduce fire risk to a minimum. Considerable space is saved by placing the gasoline and water tanks underneath the floor of this compartment in a position where they may be readily refilled. Substantially all of the space in the main compartment is available for storing the material to be transported since this compartment contains none of the apparatus of the system except a small thermostat and the refrigerating pipes. By placing these pipes underneath the roof, they are up out of the way and they may be secured in such manner as to prevent to the greatest extent, liability of being damaged or strained in such manner as to open up leaks through which the gas might escape. Furthermore the cooling effect of the pipes is utilized to great advantage by this positioning since the air which is chilled by coming into contact with the pipes tends to settle and at the same time the formation of a warm air pocket at the top is prevented because the pipes will quickly cool any warm air which tends to collect at the top. The thermostat 46 may be located at any suitable place in the main compartment and as shown is positioned on the partition wall 14. It may be located at a height which will give the best result and it may be suitably protected so that its operation will not be interfered with. The thermostat cooperates with the other elements of the starting and stopping mechanism in such manner that when the temperature rises to a predetermined maximum point, the gasoline engine and the ammonia compressor are started and when the temperature falls to a predetermined maximum point, the engine and compressor are stopped. This system may be employed to great advantage in refrigerator cars which are coupled together to form trains since each car contains a refrigerating plant which is independent from that of all of the other cars, and, therefore, one or more cars may be taken out or side-tracked and the refrigerating action will still be continued as long as desired or until the cars are unloaded. Access to the aux-

iliary and main compartments may be had through suitably placed doors of any desired construction constituting no feature of this invention, and, hence, not shown.

We claim:

- 5 1. In an automatic stopping and starting device for gasoline engines, the combination of a thermostat located in a chamber whose temperature is to be controlled, said thermostat having a movable member and fixed maximum and minimum contact points, a battery connected to said movable member, a starter generator driven by the engine, a two-part electromagnetic device one side of which 10 is connected to said maximum contact point to cause current to flow from said battery to the engine ignition and to said starter generator for starting the engine when the temperature in said chamber rises to a pre-determined point, a throw-out device operated by the engine which cuts off the supply of current from said battery to said starter generator when the engine is fully started, and a connection between the second side 15 of said two-part electromagnetic device and said minimum contact point whereby current to the engine ignition is cut off when the temperature in said chamber falls to a pre-determined point.
- 20 2. In an automatic stopping and starting device for gasoline engines, the combination of a thermostat located in a chamber whose temperature is to be controlled, said thermostat having a movable member and fixed maximum and minimum contact points, a battery connected to said movable member, a starter generator driven by the engine, a two-part electromagnetic device one side of which is connected to said maximum contact 25 point to close said device, a wire connecting said device with the engine ignition, a second electromagnetic device, a throw-out device operated by the engine and moved thereby into open position when the engine is fully 30 started, a wire connecting said first wire with said throw-out device through said second electromagnetic device, a connection between the second side of said two-part electromagnetic device and said minimum contact point to open said two-part electromagnetic device, a connection between said battery and said starter generator, said connection including the movable member of said second electromagnetic device, a cut-out device, a connection from one side of said cut-out device to said starter generator, and a connection from the other side of said cut-out device to the battery line.
- 35 3. In an automatic stopping and starting device for gasoline engines, the combination of a thermostat located in a chamber whose temperature is to be controlled, said thermostat having a movable member and fixed maximum and minimum contact points, a battery connected to said movable member, a sole-

noid core, a contact member carried thereby, a coil surrounding one end portion of said core and connected to one of said fixed contact points, a second coil surrounding the other end portion of said core and connected to the other of said fixed contact points, two contact fingers spaced from each other and adapted to be bridged by said contact member when one of said coils is energized, one of said contact fingers being connected to the battery line, a wire connecting the other of said contact fingers with the engine ignition, an electromagnetic device having a coil one end of which is connected to said wire, a grounded centrifugal throw-out device to the ungrounded side of which the other end of said last mentioned coil is connected, said device being driven by the engine, a starter generator driven by the engine, two contact members spaced from each other and bridged by the armature of said electromagnetic device when the latter is energized, one of said contact members being connected to said starter generator and the other of said contact members being connected to the battery line, a cut-out device, a connection from one side of said cut-out device to said starter generator, and a connection from the other side of said cut-out device to the battery line.

4. In an automatic stopping and starting device for gasoline engines, the combination of a thermostat located in a chamber whose temperature is to be controlled, said thermostat having a movable member and fixed maximum and minimum contact points, a battery connected to said movable member, a solenoid core, a contact member carried thereby, a coil surrounding one end portion of said core and connected to said maximum contact point, a second coil surrounding the other end portion of said core and connected to said minimum contact point, two contact fingers spaced from each other and adapted to be bridged by said contact member when the first of said coils is energized, one of said contact fingers being connected to the battery line, a wire connecting the other of said contact fingers with the engine ignition, an electromagnet having a coil one end of which is connected to said wire, a two-part ring having its parts insulated from each other, one of said parts being connected to the other end of said last mentioned coil and the other of said parts being grounded, a rotatable member driven by the engine, arms pivoted to said rotatable member, springs normally holding said arms in engagement with said ring and permitting them to be thrown out from engagement therewith by centrifugal force, a starter generator driven by the engine, two contact members spaced from each other and bridged by the armature of said electromagnet when the latter is energized, one of said contact members being connected to said starter generator and the other of said

contact members being connected to the battery line, a cut-out device, a connection from one side of said cut-out device to said starter generator, and a connection from the other side of said cut-out device to the battery line.

5 In testimony whereof we hereunto affix our signatures.
